UNITED STATES PATENT OFFICE.

EDVIN C. G. ÖBERG, OF HELSINGBORG, SWEDEN, ASSIGNOR TO OSCAR R. LUNDIN, OF BOSTON, MASSACHUSETTS.

BOX FOR HOLDING SUPERIMPOSED EDGED BLADES AND UNIT RAZOR-BLADE PACKAGES.

Application filed April 4, 1927, Serial No. 180,782, and in Sweden April 20, 1926.

This invention relates to improvements in receptacles to contain a series of superposed edged blades adapted to prevent the edge or edges of the blades from contacting with a 5 wall of the receptacle.

More particularly the invention relates to receptacles containing razor blades, particularly of the safety razor type, from which the blades can be removed in a predetermined 10 succession and into which the blades desirably can be introduced in a predetermined succession.

A further object of the invention is to provide an article of manufacture comprising 15 a plurality of superimposed razor blades contained in a receptacle of the character described in such a manner that the edges of the blades cannot contact with the walls of the receptacle and from which the blades 20 can be readily removed in a predetermined succession and after use can be readily inserted into the receptacle or box successively beneath the blades remaining in the receptacle or box.

25 Other objects and features of the invention will more fully appear from the following description and the accompanying drawings and will be particularly pointed out in the claims.

30 As is well known, razor blades, such as blades for safety shaving apparatus, retain an edge when used, only for a relatively short time and are in general not intended for re-grinding. Likewise it is a known condition that the edge of a razor or shaving 35 apparatus blade is improved by non-use, or so to speak "becomes better by lying", if the same without re-grinding or stropping is left unused for some time. The invention is 40 based upon this characteristic of edged blades and comprises means for permitting such improvement in the edge of the blade by causing the same to be unused during a considerable period before it is again employed.

45 The particular embodiment of the invention illustrated comprises a receptacle or box for holding shaving blades in such a manner that a suitable number of blades which 50 are laid therein in superposed relation can be removed from the receptacle or box only in a certain succession of order. The receptacle or box also is so constructed that the used blades are inserted in it in such a man-

ner that the last one put in is also the last 55 one to be removed from the receptacle. Thus the blades which are successively removed for use and returned to the receptacle in the same order are given an opportunity to "improve by lying" during a sufficient 60 time before they are again used.

Preferred embodiments of the invention are illustrated in the accompanying drawings, in which,

Fig. 1 is a longitudinal sectional view, 65 about twice the normal size, of a box or receptacle containing a plurality of superimposed safety razor blades;

Fig. 2 is a plan view of the box illustrated in Fig. 1 of approximately normal size;

Fig. 3 is a bottom plan view of a different construction embodying the invention,

Fig. 4 is a longitudinal sectional view of a receptacle or box embodying the invention having hinged lids directly opposite to each 75 other.

The construction illustrated in Fig. 1 is applicable to a dresser-box and is of substantially cylindrical form. It comprises a base 1, a surrounding wall 2, and a top 3 which 80 may be of integral construction, the top 3 being provided with a preferably semi-circular lid 4 secured to the top by a hinge 5 and having a peripheral flange 6 adapted to fit over the edge of the surrounding wall 2. 85 The base 1 is also provided with a preferably semi-cylindrical lid 7 having a peripheral flange 8 fitting the surrounding wall 2. The base 1 desirably is provided with an aperture 9, directly beneath the lid 4, through 90 which the finger of the operator may be inserted to raise the pile of superimposed blades sufficiently to enable the uppermost blade readily to be withdrawn from the box. The lids 6 and 7, of course, need not be of 95 semicylindrical form, nor need they be hinged to the top or bottom of the box. If desired the hinged lid could be replaced by a sliding lid or one which is wholly removable although such construction would be less 100 suitable if applied to a cylindrical box.

The superimposed blades desirably are separated from each other by intermediate layers of water-repellant material, such as impregnated paper. These layers, when a 105 cylindrical box is employed, desirably are of circular form.

Usual types of safety razor blades are

provided with substantially circular ends and the cylindrical wall 2 of the box desirably is complementary to the circular ends of the blades and of a slightly greater diameter than the maximum length of the blades. By reason of this construction the circular wall of the box is adapted to engage the ends of the blade in such a manner as to maintain the blades in parallelism even though they rotate within the box and also acts to prevent the edges from coming into contact with the wall of the box.

The box can be made of any suitable material and provided with any desired ornamentation.

A box of the character described with a predetermined number, such, for example, a dozen blades, is sold as an article of manufacture. When it is desired to use a blade the lid 4 of the box is opened, as illustrated, and the finger of the operator inserted through the aperture 9 in the bottom thereof a sufficient distance to lift the superimposed blades until the uppermost blade lies slightly above the edge of the surrounding wall 2 of the box. The uppermost blade can then be slipped readily from the box and used. After the blade has been used it should be returned to the box at the bottom of the pile of superimposed blades. This can be done by opening the lid 7 of the bottom of the box and inserting the blade beneath the pile of blades therein. Of course, the separating member can be removed from the box at the time the blade is removed, and inserted in the bottom of the box before the used blade is returned to it, thus maintaining the blades out of contact at all times. By thus, each time, removing the uppermost blade for use, and after use inserting the same beneath the pile of blades remaining in the box, each blade is given a period of rest sufficient to "improve by lying".

In Fig. 3 a modified construction is illustrated in which the receptacle or box is of general rectangular form, the side walls 10 and 11 being parallel to the edges of the blades and the end walls 12 complementary to the circular ends of the blades. In this construction, however, the blades desirably are provided with recesses 13 centrally of their ends and the end walls 12 of the box are preferably provided with indentations 14 complementary to the recesses 13 in the ends of the blades.

The recesses in the blades when engaging the inwardly projecting indentations of the wall prevent sufficient lateral movement of the blades to enable the edges thereof to engage the side walls 10 and 11 of the receptacle. In this construction care must be taken to prevent the edges of the blades from engaging the walls 10 and 11 of the box when the blades are removed or inserted. In this type of construction a sliding

lid or a wholly removable lid may be employed.

In this construction a lid 15 is hinged to the top of the box, preferably about midway of the length thereof, and a corresponding lid 16 is similarly hinged to the bottom of the box. The bottom of the box desirably is provided with an aperture 17 for the insertion of the finger to aid in removing the blades from the box as aforesaid.

In the construction illustrated in Fig. 4 the body of the box comprises an integral construction having a top wall 18 and a bottom wall 19 preferably integrally connected by a peripheral wall 20. Oppositely disposed lids 21 and 22 are hinged respectively to the top 18 and bottom 19. The lids are provided with complementary side flanges 23 and 24 and overlapping end flanges 25 and 26 either adapted to, or having means to clamp the same together when they are swung into closed position, as illustrated in dotted lines in Fig. 4.

Cheaper commercial packages can be constructed by providing the box with one lid only. This will, however, necessitate the removal of the entire pile of blades when a used blade is to be inserted in the proper order above described.

The embodiments of the invention disclosed herein are of an illustrative character and are not restrictive. It will, therefore, be understood that other forms of boxes may be employed and that various changes in construction and arrangement of parts may be made within the spirit and scope of the following claims.

Having thus described the invention, what is claimed as new, and desired to be secured by Letters Patent, is:

1. A box for a plurality of like superimposed blades comprising a casing to enclose said blades having means to engage the ends of the blades acting to prevent engagement of the edges thereof with the wall of the box and means for permitting the removal of the blades in predetermined succession from one side of the box and the insertion of the blades in the same succession into the other side of the box.

2. A box for a plurality of like superimposed edged blades comprising a casing having a base, a surrounding side wall formed to engage the ends of the blades and acting to prevent engagement of the edge or edges of the blades with the surrounding wall and a top having a hinged lid section to permit the removal of said blades successively for use, and an aperture in the bottom beneath said lid.

3. A box for a plurality of like superimposed edged blades comprising a casing having a base, a surrounding side wall formed to engage the ends of the blades and acting to prevent engagement of the edge or

edges of the blades with the surrounding wall and a top having a hinged lid section to permit the removal of said blades successively for use, said base being provided with a hinged lid to permit the insertion of the used blades beneath the pile of superimposed blades in the box.

4. A box for a plurality of like superimposed edged blades having circular ends comprising a relatively thin cylindrical receptacle having an inside diameter slightly greater than the maximum length of the blades and having a top having a rigid section extending over a part of the receptacle and a lid hinged thereto extending over the remainder of the receptacle.

5. A box for a plurality of like superimposed edged blades having circular ends comprising a relatively thin cylindrical re-

ceptacle having an inside diameter slightly greater than the maximum length of the blades and having a top provided with a hinged lid extending over a portion thereof, the base of said box being provided with an aperture directly opposite said lid. 20 25

6. A box for a plurality of like superimposed edged blades having circular ends comprising a relatively thin cylindrical receptacle having an inside diameter slightly greater than the maximum length of the blades and having a top provided with a hinged lid, the base of said box being provided with an aperture directly opposite said lid, and the bottom of the box having also a hinged lid section. 30 35

In testimony whereof, I have signed my name to this specification.

EDVIN C. G. ÖBERG.
